WIRELESS RECEIVER

Hubert Cyril Atkins, Hayes, England, assignor to
 Victor Talking Machine Company, a corpora-
 tion of New Jersey

Application September 25, 1930, Serial No. 484,340
 In Great Britain October 16, 1929

2 Claims. (Cl. 250—20)

The present invention relates to wireless receivers employing a volume control in which the volume control takes the form of a potential divider shunted across the aerial circuit.

5 In such a receiving system the tuning of the input circuit of the receiver depends to some extent at least upon the capacity to earth of the aerial, this capacity to earth being, in effect, a condenser connected across the input circuit.

10 As the tapping point on the potential divider is varied, however, the amount of this capacity across the input circuit varies and consequently this circuit tends to become detuned.

It is an object of the present invention to prevent or reduce the detuning effect produced in the input circuit of a wireless receiver by the variation in the capacity to earth of the aerial.

According to the present invention this object is attained by providing in a wireless receiving system having a volume control in the form of a potential divider connected across the aerial circuit means for preventing or reducing the detuning effect caused by the alteration in the effective capacity across the input circuit comprising a small condenser connected effectively in series between the input circuit of the receiver and the capacity to earth of the aerial.

The invention will be described by way of example with reference to the accompanying drawings in which

Fig. 1 shows the invention as applied to a wireless receiver employing transformer coupling between the aerial and input circuits, whilst

Fig. 2 shows the invention as applied to a receiver employing a single tapped coupling coil, or auto transformer.

Referring to Figs. 1 and 2 a high resistance 1 constituting a potential divider is connected between the aerial and earth and the received oscillations are transferred from the aerial to the grid circuit of the first valve of the receiver through a high frequency transformer 2, 3. A small condenser 4 is connected between the variable contact of the potential divider and one end of the primary winding 2 of the transformer, the other end of the primary winding being connected to earth. The ends of the secondary winding 3 of the transformer are connected to the grid and filament respectively of the first valve 5 of the receiver. This valve may be a detector valve or a high frequency amplifier. The filament of the valve is connected to earth and a variable condenser 6 is connected across the secondary winding of the transformer. The resultant of the capacity of the small condenser 4 and

the aerial capacity in series (shown diagrammatically by reference 7) is smaller than the capacity of the small condenser alone and the total capacity effectively in parallel with the primary winding of the transformer therefore remains substantially constant notwithstanding the variations in the effective aerial capacity due to movement of the tapping point on the potential divider.

Although the invention has been described with particular reference to a receiving system employing transformer coupling between the aerial and input terminals, it can also be applied to systems using other forms of coupling. For example, in Fig. 2, the invention is shown as applied to a receiving system employing a single tapped coupling coil or autotransformer 2 in place of the usual high frequency transformer, the terminals of the coil being connected to the grid and filament respectively of the first valve 5 of the receiver. The condenser 4 is connected between the variable contact of the potential divider and the tapping on the coil 2.

I claim:

1. In a radio receiving system, a resistor having terminals adapted, respectively, to be connected to an antenna and to ground, a high frequency transformer having input and output terminals, a connection between one of the input terminals and the ground terminal of the resistor and a connection serially including a capacitor and an adjustable contact device between the other input terminal and the resistor, the capacitor being so chosen with respect to the expected antenna capacity to ground that the resultant series capacity is less than that of the capacitor, whereby the total capacity effectively in parallel with the primary of the transformer remains substantially constant notwithstanding variations in the effective antenna capacity caused by adjustment of the contact device for the purpose of volume control.

2. The invention set forth in claim 1 further characterized in that an adjustable condenser is connected in shunt relation to the secondary of the high frequency transformer.

HUBERT CYRIL ATKINS.
